UNITED STATES PATENT OFFICE

HENRY L. PITMAN, OF WESTFIELD, NEW JERSEY, ASSIGNOR, BY MESNE ASSIGNMENTS, TO ELLIOTT-FISHER COMPANY, OF NEW YORK, N. Y., A CORPORATION OF DELAWARE

COMBINED TYPEWRITING AND COMPUTING MACHINE

Original application filed February 11, 1926, Serial No. 87,533. Divided and this application filed June 22, 1927. Serial No. 200,518.

This invention relates to tabulating mechanism in combined typewriting and computing machines of the Underwood-Hanson type, where power-driven means operate to line-space the platen and return the platen-carriage to a new line-starting position, and from which position tabulating keys and associated means quickly re-position the carriage denominational within predetermined column 10 fields.

In a combined typewriting and computing machine the operation of typewriter-keys to write a number in a computing zone may simultaneously cause said number to be set up 15 computatively by means which include a tappet carried on the typewriter-carriage, and which actuate denominational jacks to successively select the denominational pin-bars in which the number is set to be subsequently 20 transferred to computing wheels. As the carriage enters a computing zone the tappet is lifted into position to engage the denominational jacks by means of a supporting member over and along which the tappet rides. 25 To avoid actuation of the denominational jacks during tabulating movements of the carriage the supporting member is withdrawn when a tabulating key is operated and causes 30 the tappet to fall slightly and clear the denominational jacks.

One object of this invention is to provide means whereby an operative may stop the power-driven return movement of the carriage by operating a tabulating key and cause 35 the immediate positioning of the carriage for writing and computing in an intermediate place on the work-sheet without fully returning the carriage to the initial line-starting position. This is of great advantage in cases 40 where entries are written and computed in different columns on the work-sheet. Thus, as soon as the power-driven means has returned the carriage, so that the column on the work-sheet in which it is desired to make an 45 entry is past the printing point, a tabulating key may be depressed and the return movement of the carriage is thereby stopped for lack of driving power and a tabulating movement of the carriage toward the left immedi- 50 ately occurs under the power of its own dry-

ing spring and which is arrested when a column-stop on the carriage strikes the decimal-stop raised in its path by the tabulating key.

By means of suitable connections the movement of the usual universal bar coacting with 55 the decimal tabulating stops to disengage the carriage-feed rack from its pinion is also used to simultaneously disengage the carriage-return driving mechanism. This is preferably accomplished by extending the shaft on which 60 the tabulating universal bar is mounted and fastening an arm thereon to reach and engage the usual linkage by means of which the carriage-return mechanism is engaged, but which, according to the present invention, 65 may be also used to disengage the carriage-return mechanism.

Another object of the present invention is to provide simple means whereby any tabulating key in operating its universal bar will 70 cause the tappet-supporting member to be withdrawn against the action of a spring or other device, which tends to keep the tappet-supporting member in its effective position, and in the present invention the withdrawal 75 is accomplished without putting the burden of said spring action upon the tabulating key. The tabulating key may thus be operated with a normal light touch. To this end, when a tabulating key is operated, a power-driven 80

pin is projected into the plane of an arm fastened to a rock-shaft supporting the tappet-supporting member. The pin is simultaneously caused to revolve about a suitable axis, so that it describes a path intercepting said 85 arm and is thus operative to displace said arm, thereby effecting the withdrawal of the tappet-supporting member. The power-driven pin may be projected by the tabulating key-actuated universal bar, and a flexible spring- 90 pressed connection that will yield should the pin encounter the face of the arm, escape therefrom, and spring forward due to the spring tension of said flexible connection. Latching means are provided to hold the tappet-supporting member in ineffective position until the tabulating key is released. 95

Another object of this invention is to provide means whereby starting and stopping of the motor may be controlled by means of the 100

same circuit-closing device or switch regularly provided for the carriage-return mechanism. This device is actuated upon releasing a train of spring-pressed linkage, by 5 means of which the carriage-return mechanism is engaged. A bar pivoted to this linkage extends toward and interlocks with the circuit-closing device, so as to normally keep it open. When the linkage is released to engage 10 the carriage-return mechanism this bar is withdrawn, and the circuit-closing device which includes a spring-pressed arm is closed.

In the present invention, the switch bar or other suitable actuator, by means of which 15 the circuit-closing device is opened or closed, is connected to the carriage-return linkage in such a way that it may be operated independently of said linkage, making it possible to disengage the carriage-return mechanism 20 without stopping the motor when a tabulating key is operated, or to operate the circuit-closing device independently of the carriage-return mechanism linkage, or to operate the circuit-closing device in the usual way when 25 the carriage-return mechanism is engaged or disengaged. To this end, the switch bar or actuator for the circuit-closing device or switch is preferably connected to the carriage-return mechanism linkage by means of a pin 30 and inclined slot device and is slidably supported by the previously-mentioned arm, which disengages the carriage-return mechanism when a tabulating key is operated.

The carriage-return mechanism is engaged 35 by pressing the usual carriage-return key, or the engagement is effected automatically by the usual means associated with the left-hand marginal carriage-stop.

This application is a division of my application 40 Serial No. 87,533, filed February 11, 1926.

Other features and advantages will herein-after appear.

In the accompanying drawings, 45 Figure 1 is a sectional elevation of an Underwood-Hanson combined typewriting and computing machine, and shows only such part of the typewriter-mechanism and computing mechanism as is necessary to illustrate the invention.

Figure 2 is a detail view of the principal letter-feeding elements.

Figure 3 is a view of the switch for starting and stopping the motor which operates the 55 carriage-return mechanism and other devices of this invention.

Figure 4 is a skeleton perspective view of the tabulating mechanism and the means by which the tappet-supporting member is withdrawn.

Figure 5 is a rear view of parts shown in Figure 4.

Figure 6 is a detail perspective view of the pin-and-slot connection for the switch-actuating element.

Figure 7 is a detail view showing the relation of the parts when a tabulating key is operated and the tappet-supporting member is about to be withdrawn.

Figure 8 is a detail view showing the tappet-supporting member withdrawn, and also showing the means by which it is latched in its withdrawn position.

Figure 9 is a detail view showing the operation of the flexible connection as it yields, if the operating pin is projected against the arm that withdraws the tappet-supporting member.

Figure 10 is a detail view showing the relation of the parts when the carriage-return mechanism alone is engaged.

Figure 11 is a diagram showing the electrical connections.

The Underwood typewriter forming a part of the machine to which this invention is applied, is provided with a decimal tabulating mechanism, which includes keys 11 upon levers 12 fulcrumed at 13. The rear ends 14 of said levers, when operated, raise decimal-stops 15, so that the upper ends 15^a thereof are in the path of column-stops 16 on the typewriter-carriage 17. The decimal-stops and tabulating keys are retracted against a stop 17^a by springs 18 applied to said decimal-stops. Each decimal-stop 15 has a notch 19 95 to engage a universal bar 20 mounted upon a shaft 21. Said universal bar, when operated by any of the decimal-stops when a tabulating key is depressed, disengages a carriage-feed rack 22 from its pinion 23 by means 100 which include an arm 24, a link 25 and a lever 26. Said lever is pivoted at 27 and connected to said link at 28 and carries a roll 29, which lifts the letter-feed rack upward and holds it disengaged from its pinion during the tabulating movement of the carriage.

Numerals 30 and alphabet-keys 31 by means of the usual key-levers, not shown, and bell-cranks 32, partly shown, swing type-bars 33 upwardly and readwardly about a fulcrum 34 to print against a platen 35 around which a work-sheet, not shown, may be fed. Heels 36 upon the type-bars actuate a universal bar 37 connected to a dog-rocker 38, which includes a fixed dog 39 and has mounted thereon a stepping dog 40. Said dogs co-operate with an escapement-wheel 41 to which is connected the pinion 23. The carriage is propelled in a letter-feeding or tabulating direction by a spring-motor 42.

When the carriage moves in letter spacing and reaches a left-hand marginal carriage-stop, not shown, a lug 43 on the carriage actuates a cam-lever, not shown, on said left-hand marginal stop to swing a marginal stop-rack 44 about a fulcrum 45. Pivoted connected to said marginal stop-rack at 46 is a link 47 which extends downwardly and is connected to one end of a lever 48 pivoted upon the typewriter-frame 49 at 50. The other end 125

of the lever 48, when actuated, engages a pin 51 fastened in the side of a carriage-return trip-link 52 and lifts said trip-link, which is pulled rearwardly by a spring 53. Said trip-link is normally held by a plate 54 which engages a notch 52^a in said link 52. The rear end of the link is pivotally connected to an arm 55 keyed to a shaft 56. As the carriage in its letter-feeding movement or otherwise reaches the line-end marginal stop, the carriage-return trip-link 52 is released from its holding plate and its movement by the spring 53 causes the rotation of the shaft 56. The carriage-return trip-link may also be released by means of a manually operated lever 55^a pivoted on the typewriter-frame at 56^a. Said lever when operated raises the forward end of the trip-link 52 to release it from the plate 54 through the camming of a by-pass pawl 57 by the tip 57^a of said lever as it is operated. The lever 55^a is returned to its normal position against a stud 58^a by a spring 59^a, and is ineffective to release the link on account of said by-pass pawl. Fastened to said shaft is another arm 58 which is connected by means of a link 59 to an arm 60 fastened to a shaft 61, upon which is fastened an arm 62, which engages a slidable clutch-member 63. As the shaft 61 is rotated by means of the aforesaid connections through the movement of the link 52, the clutch-member 63 actuated thereby slides into engagement with a clutch-member 65 keyed to a shaft 66. Said shaft 66 has its bearing in a bracket 67 attached to the typewriter-frame 49 in the usual manner. A pulley 68 is keyed to said shaft 66, and by means of a belt 122 is connected to a driving motor 70. Said driving motor 70 is controlled by a switch indicated at 71, Figures 3 and 11, actuated by a connection from the link 52, to an arm 72, fastened to the shaft 56 to operate a switch bar 77. In the end of said arm 72 is a stud 73, which has a shoulder 74, and a head 75, to be assembled through a cam-slot 76 in the end of the switch bar 77, see Figure 6. After the cam-slot 76 has been placed over said head 75, the stud 73 may be given a quarter turn, so as to retain said cam-slot 76, the stud 73 then being secured to the arm 72 by any suitable means, as by a lock-nut 73^a. The bar 77 is slidably supported upon an arm 78 and between pins 79 projecting from said arm. The purpose of said arm 78 will presently be described. It will be seen that, as said shaft 56 is rotated, as when the clutch-members 63 and 65 are engaged, Figure 10, the bar 77 will move longitudinally to close the switch contained within a casing 77^a. For flexibility the bar 77 has slidably mounted thereon a member 69 connected to said rod by a spring 69^a. The rear end of said member engages the switch to close it. After closing said switch the bar 77 has an excess movement during which the spring 69^a yields.

When the typewriter is used with a computing mechanism, there are mounted on its carriage tappets 80 supported by rods 81 and 82, the rod 81 serving as a fulcrum for the tappets 80 which are raised by the usual tappet-supporting member 83. Said tappet-supporting member 83 is coextensive with a series of jacks 84 pivoted at 85 and engageable by a one-way pawl 87 mounted upon each tappet 80, and each tappet is upheld as it rides over the tappet-supporting member 83 by means of a roll 87^a fastened to said tappet. In this manner, the carriage, moving step by step through a computing zone, operates at each step one of the jacks 84 and causes a downward thrust of a rod 88, to select in the usual manner one of the computing machine pin-bars which are not shown. The computing mechanism is of the type shown in the patent to O. Minton, No. 1,280,065, dated September 24, 1918. The tappet-supporting member 83 is supported between arms 89 fastened to a rock-shaft 90, which is pivoted between brackets, not shown, upon the typewriter-frame 49. The usual spring-device 91, described in the patent to W. L. Gumprecht, No. 1,268,565, dated June 4, 1918, operates to keep the tappet-supporting member 83 in effective position to raise each tappet 80, so that it may engage the jacks 84.

When tabulating the carriage it is desirable to withdraw the tappet-supporting member 83, so that the pawl 87 on the tappet will not operate the jacks 84 during the comparatively rapid movement of the carriage as it is tabulated. The withdrawal of the tappet-member 83 is effective against the reaction of the spring-device 91, and to avoid putting the burden of overcoming this reaction upon the tabulating key, means are provided to withdraw the tappet-supporting member 83 by power when a tabulating key is operated. To this end, there is mounted upon the rock-shaft 90 an arm 92, which has a cam-formation 93, see Figure 5. When a tabulating key is operated, there is projected into the plane of this cam-formation 93 a pin 94, said pin being projected through a hole 95 in the web of the pulley 68. This pin may be mounted upon a disk 96 which slides upon a bearing 97 formed upon the bracket 67. To slide the pin 94 forward and backward, a groove 98 is formed in a hub of said disk 96 to be engaged by a pair of arms 99 mounted on a shaft 100, and yieldably connected thereto by means of a spring 118. One end of said spring is fastened to the shaft 100 by means of a collar 119, and the other end presses the arms 99 which are held by a stud 120 driven through a slot 120^a in a hub 121^a of the arms 99 into the shaft 100. Should the pin 94 be in a position where its projection would be obstructed by the arm 92, the spring 118 will yield until the pin has passed said arm. Said shaft is pivotally supported in a hole 130

101 in the tabulator-stop-frame and in a hole 102 in a lug 121 fastened to the bracket 67. To rotate said shaft 100 and project the pin 94 into the plane of the cam-formation 93 whenever a tabulating key is operated, said shaft is further provided with an arm 103 fastened thereto and connected by means of a link 104 to the link 25, which is used to disengage the carriage-feed rack. It will be remembered that this link 25, connected to the universal bar 20 by means of the arm 24, is operated whenever a tabulating key is depressed, and is effective to rotate the shaft 100 to drive the pin 94 into the plane of the cam-formation 93 and the motor 70 is simultaneously started, to drive the belt 122 to cause the pulley 68 and pin 94 to revolve to rock the shaft 90.

To start the motor the depression of any tabulating key vibrates the arm 78 provided with pins 79 carrying the forward slotted end of bar 77, and the arm 72 and its stud 73 being at this time stationary, the bar 77 is shifted rearwardly, due to the inclination of cam-slot 76, to close the switch 71, start the motor, rotate the pulley 68 and cause the projected pin 94 as it revolves to displace the arm 92, to rock the shaft 90 and effect the withdrawal of the tappet-supporting member 83.

It will be seen that when the revolving pin 94 has passed the cam-formation 93, the tappet-supporting member 83 tends to return to tappet-raising position again. To prevent this until the tabulating key is released, a latch 105 is provided and is pivoted to one of the arms 89 at 106, and is pressed by a spring 107, so that normally an extension 108 of said latch 105 bears against the shaft 100. When a tabulating key is depressed causing the shaft 100 to rotate, an arm 109 thereon raises said latch by means of a lug 110 projecting from said latch. As the tappet-supporting member 83 is withdrawn, the latch is pulled rearwardly and the lug 110 falls behind a holding edge 111 on the arm 109. It will be seen that when the tabulating key is released the arm 109 will be withdrawn from said lug 110, and the tappet-supporting member resumes its normal position.

Heretofore in an automatic carriage-return there was no way of stopping the carriage-return movement until the carriage had reached the right-hand marginal carriage-stop and rotated a shaft 112 by the usual means, which included a dog 113 keyed to said shaft 112 and actuated by the lug 43. As said shaft 112 is rotated it disengages the clutch-elements 63 and 65 by means which include an arm 114, fastened to said shaft 112, a link 115, a sliding member 116 and an arm 117 fastened to the shaft 61. Details of the means associated with the left and right hand marginal carriage-stops to engage and

disengage the carriage-return mechanism, are set forth in the patent to R. F. Hoyt, No. 1,238,919, dated September 4, 1917.

Previously, whenever it was desired to make an entry in an intermediate column on the work-sheet or a correction in a computing zone, it was necessary to always return the carriage to its line-starting position as determined by the right-hand marginal carriage-stop, and then to tabulate anew to the place where the entry was to be made. If several columns intervened between the starting point and the place the entry was to be made, such columns could only be skipped by successive operations of the tabulating keys. To avoid this, means are provided whereby, as soon as the carriage has returned far enough so that the column in which it is desired to make the next entry is past the printing point, the return movement of the carriage may be stopped by pressing the proper denominational tabulating key. The carriage as soon as its return movement is thus stopped for lack of driving power will be immediately tabulated under the power of its own spring-drum to the proper denominational column position according to the key depressed, and said key is held depressed until the carriage is thus tabulated. To accomplish this the previously-mentioned arm 78 has a camming edge 123 co-operative with the surface 124 of the stud 73, and effective whenever a tabulating key is depressed to cam the arm 72 aside, thereby causing the restoration of the linkage 58-62 which has effected the engagement of the carriage-return clutch-members 63 and 65. The circuit to the motor, however, is not broken as long as the tabulating key is depressed, so that the tappet-support 83 is withdrawn in the manner described, and the bar 77 held in its circuit-closing position until the tabulating key is released.

It will be noted that the depression of the carriage-return key starts the motor 70 and closes a clutch 63-65, whereby the motor will drive the carriage in a carriage-return direction to a marginal-stop position, which determines the line-starting position for the carriage automatically and independently of the carriage-return key and disables the motor-clutch to arrest the carriage; that the carriage-spring is always effective to drive the carriage in letter-spacing or column-spacing direction when a tabulating key is depressed; that the carriage-return motor overcomes the opposition of the carriage-spring in returning the carriage; that, when the tabulating key is depressed after a carriage-return movement is initiated, the carriage is disconnected from the rotating return motor and is brought to a stop from lack of motor-driving power, the carriage responding to the tension of its own spring until the carriage-stop strikes the tabulator-stop raised in its path,

- by the depression of the tabulating key; that the depression of any denominational tabulating key vibrates a universal bar having camming connections that effect the separation of the carriage-feed rack from its feeding and holding pinion to release the carriage to its driving spring, and restores the key-released trip-link 52 to its normal position, but does not withdraw the switch-bar 69 to break the circuit to the return motor, which continues to rotate to prevent the accidental restoration of the tappet-roller 83 until the carriage has fully advanced to the tabulating position within a column-area; that, when the tabulating advance of the carriage is completed and the tabulating key is released, the restoration of the parts from the Figure 8 positions to the positions of Figures 7 and 9 is effected by the return of the universal bar 20 where the lifting of the link 25 rocks the shaft 100 to withdraw the pin 94, vibrates the arm 109 to release the latch 105 to restore the roller 83 to lift the tappet 80, and vibrates a jack 84 corresponding to the decimal value of the key depressed; that the restoration of the universal bar also vibrates the arm 78 to effect the withdrawal of the switch-bar 77 to open the switch 71 and stop the motor 70; that an operator can readily and expertly manipulate the tabulating keys to cut into the carriage-returning movement very close to the right-hand margin of a column-area or even between adjoining column-fields, and then immediately arrest the carriage at a denominational position therein, thus avoiding the useless operation of fully restoring the carriage rightward and then advancing the carriage, column by column, as heretofore practiced, except where complicated column-skipping mechanism is employed which does not tabulate denominationally; and that an operator can limit the returning movement of the carriage to a column-width, if desired, and tabulate directly to the denominational position therein, thus providing an important time and labor saving mode of operation and giving the operator a complete carriage-direction control without removing the hands from the keyboard.
- Variations may be resorted to within the scope of the invention, and portions of the improvements may be used without others.
- Having thus described my invention, I claim:
1. In a combined typewriting and computing machine, the combination with typewriting mechanism including a letter-feeding carriage and column-stops, of means including pressible keys for positioning said carriage according to said column-stops, computing mechanism including denominational jacks for transferring numbers written by said typewriting mechanism to said computing mechanism, one or more loose tappets moving in unison with or upon said carriage to actuate said jacks, one or more spring-pressed tappet-supports to hold said tappets, so that they may operate said jacks, a carriage-return mechanism including a motor, means for engaging said carriage-return mechanism and for starting said motor, means operable by pressing any one of said keys whereby said carriage-return mechanism if previously engaged is disengaged without stopping said motor, said motor continuing to rotate until said key is released, means whereby said motor is started if said carriage-return mechanism is not engaged, and means also operable by said pressing of said key whereby said rotation of the motor causes the withdrawal of said tappet-supports, thereby disconnecting the typewriting and computing mechanisms.
  2. In a combined typewriting and computing machine, the combination with typewriting mechanism including a letter-feeding carriage, means including a tabulating key for positioning said carriage in predetermined zones, and computing mechanism, of means controlled by said carriage for operatively connecting said typewriting mechanism to said computing mechanism while the carriage is in said zones, carriage-return mechanism including an electric motor and a pair of switch contacts normally separated to render said motor silent, means whereby said carriage-return mechanism is engaged and said switch contacts are brought together to start said motor, means operable by said tabulating key to bring said switch contacts together independently of said carriage-return mechanism and rotate said motor, and means whereby the rotation of the motor, when effected by said tabulating key, also renders the connection between said typewriting and computing mechanisms ineffective.
  3. In a combined typewriting and computing machine, the combination with typewriting mechanism including a letter-feeding carriage and computing mechanism, of spring-pressed means whereby operative connection between said typewriting and computing mechanisms is normally maintained, pressible tabulating keys, carriage-return mechanism including control linkage therefor and an electric driving motor, a motor-control switch, means operable by said motor when one of said keys is pressed to operatively disconnect said typewriting and computing mechanisms, a movable switch-actuating element, a member which is displaced by pressing and releasing one of said keys, a connection between said member and said switch-actuating element, whereby said element is displaced when said member is displaced, and a pin-and-cam slot connection whereby said switch-actuating element is connected to said carriage-return mechanism control linkage, said connection being effective to close and open said switch when said control linkage

for said carriage-return mechanism is actuated, or when said one of said keys is pressed and released.

4. In a combined typewriting and computing machine, the combination with typewriting mechanism including a letter-feed carriage, and computing mechanism, of means depending on the letter-feed movement of the carriage whereby operative connection between said typewriting and computing mechanisms is normally maintained, tabulating keys, carriage-return mechanism including an electric driving motor, a motor-control switch including a pair of contacts normally separated to render said motor silent, means controlled by said tabulating keys and operable by said motor to render the connection between said typewriting and computing mechanisms inoperative during a tabulating carriage movement, and means whereby said contacts are brought together and separated by engaging and disengaging said carriage-return mechanism or by pressing and releasing any one of said tabulating keys.
5. In a combined typewriting and computing machine, the combination with typewriting mechanism including a letter-feed carriage and computing mechanism, of spring-pressed means whereby operative connection between said typewriting and computing mechanisms is normally maintained, pressible tabulating keys, carriage-return mechanism including an electric driving motor, a motor-control switch, means controlled by said tabulating keys and operable by said motor to operatively disconnect said typewriting and computing mechanisms, means including a key to engage said carriage-return mechanism, carriage-control means to engage and disengage said carriage-return mechanism, means operable by pressing said tabulating keys to disengage said carriage-return mechanism, and means whereby said switch is closed and opened either by engaging and disengaging said carriage-return mechanism independently of said tabulating keys or by pressing and releasing any one of said tabulating keys when said carriage-return mechanism is disengaged, said last-named means being also effective to keep said switch closed as said carriage-return mechanism is disengaged by pressing any one of said tabulating keys.

6. In a combined typewriting and computing machine, the combination with typewriting mechanism including a letter-feeding carriage and computing mechanism, of spring-pressed means whereby operative connection between said typewriting and computing mechanisms is normally maintained, a shaft on which said spring-pressed means is mounted, an arm on said shaft, pressible tabulating keys, a revolvable element, means operable by any one of said keys to project said element into the plane of said arm, means

to revolve said element about an axis, so that said element describes a path normally intersected by said arm and displaces said arm from said path, thereby rocking said shaft and causing the operative disconnection of said typewriting and computing mechanisms, and means whereby said disconnection is maintained while said key is pressed.

7. In a combined typewriting and computing machine, the combination with typewriting mechanism including a letter-feeding carriage, computing mechanism, and a driving motor for certain operations of said mechanisms, of means depending on the letter-feed carriage movement whereby operative connection between said typewriting and computing mechanisms is normally maintained, a shaft rotatable to shift said means and render said connection ineffective, an arm on said shaft, tabulating keys, a revolvable element connected to said motor and normally clearing said arm, means operable by any one of said keys and including a yieldable device, whereby said arm and said revolvable element are relatively displaced, so that said revolvable element may engage said arm for rotating said shaft, said yieldable device becoming effective if said element and said arm happen to be in a position where their relative displacement would otherwise be obstructed by each other, said element describing a circular path normally intersected by said arm for displacing said arm from said path, and thereby causes the operative disconnection of said typewriting and computing mechanisms, and means whereby said disconnection is maintained while said key is pressed.

8. In a combined typewriting and computing machine, the combination with a letter-feeding typewriter-carriage, and computing mechanism including denominational elements, of a shiftable device spring-pressed into effective position whereby said carriage in its letter-feed movements is enabled to successively engage and displace said denominational elements, key-controlled carriage-tabulating mechanism, a tappet, means for mounting said tappet for circular revolution about an axis to engage and displace said shiftable device, said mounting means arranged so that said tappet is normally retracted to clear said device, power-driven means for revolving said tappet, and means whereby the engagement of said tabulating mechanism causes the revolution of said tappet and concomitantly projects said tappet into position for engaging and displacing said device so that the carriage in a tabulating movement is relieved of displacing said denominational elements.

9. In a combined typewriting and computing machine, the combination with a letter-feeding typewriter-carriage, and computing mechanism including denominational ele-

ments, of a shiftable device spring-pressed into effective position whereby said carriage in its letter-feed movements is enabled to successively engage and displace said denominational elements, key-controlled carriage-tabulating mechanism, a tappet, means for mounting

5 said tappet for circular revolution about an axis to engage and displace said shiftable device, said mounting means arranged so that 10 said tappet is normally retracted to clear said device, power-driven means connectible to effect a return movement of said carriage opposite to the letter-feeding and tabulating movements, said power-driven means also

15 effective to revolve said tappet, and means whereby engagement of said tabulating mechanism is effective to disconnect the carriage from said power-driven means if said carriage is so connected, and concomitantly 20 cause the projection of said tappet into position for engaging and displacing said device so that the carriage in a tabulating movement is relieved of displacing said denominational elements.

25 10. In a combined typewriting and computing machine, the combination with a letter-feeding typewriter-carriage, and computing mechanism including denominational elements, of a shiftable device spring-pressed 30 into effective position whereby said carriage in its letter-feed movements is enabled to successively engage and displace said denominational elements, key-controlled carriage-tabulating mechanism, power-driven rotatable means, means for conditioning said rotatable means to engage and return said carriage, 35 means called into action by operation of said tabulating mechanism, to condition said rotatable means to be effective for displacing 40 said shiftable device so that the carriage in a tabulating movement will be relieved of displacing said denominational elements, a member shiftable for starting and stopping said rotatable means, and means whereby initiation and termination of the carriage-returning operation or tabulating operation 45 may actuate said member to correspondingly start and stop said rotatable means.

11. In a combined typewriting and computing machine, the combination with a letter-feeding typewriter-carriage, and computing mechanism including denominational elements, of a shiftable device spring-pressed 50 into effective position whereby said carriage in its letter-feed movements is enabled to successively engage and displace said denominational elements, key-controlled carriage-tabulating mechanism, power-driven rotatable means, means for conditioning said ro- 55 tatable means to engage and return said carriage, means whereby the operation of said tabulating mechanism may arrest the return movement of said carriage and effect tabulation of said carriage in a direction contrary 60 to said movement before said carriage is fully

65 returned to a line-starting position, means called into action by operation of said tabulating mechanism to condition said rotatable means to be effective for displacing said shiftable device so that the carriage in a tabulating movement will be relieved of displacing said denominational elements, a member shiftable for starting and stopping said rotatable means, and means whereby the initiation of the carriage-return operation 70 may be effective upon said member to start said rotatable means, and the termination of the tabulating operation may be effective upon said member to stop said rotatable means.

75 12. In a combined typewriting and computing machine having computing mechanism, a letter-feeding carriage, a motor, carriage-return mechanism operable by said motor, and mechanism for tabulating said carriage in a letter-feeding direction, the combination with means operable by said motor and controlled by said tabulating mechanism for disabling said computing mechanism during a tabulating movement of said carriage, of motor-control means whereby said motor may be started and stopped in concomitance with the initiation and termination of either a carriage-return operation or a tabulating operation, and whereby said carriage-return movement may be stopped by initiating a tabulating operation, and the motor kept running to disable the computing mechanism, said motor-control means including a motor-control member shiftable to start and 80 stop said motor, an element vibrated by said tabulating mechanism to engage and displace the carriage-return mechanism to stop a carriage-return movement, said motor-control member having a cam-and-pin connection to 85 said carriage-return mechanism, and a sliding support on said vibrated element, said cam-and-pin connection and sliding support constraining said motor-control member to be 90 conditioned to start and stop said motor or 95 keep it running as aforesaid.

100 HENRY L. PITMAN.
